UNITED STATES PATENT OFFICE.

NOBLE R. MEDEARIS, OF WINSTON-SALEM, NORTH CAROLINA.

INDEX FOR RUBBER STAMPS.

1,325,569.

Specification of Letters Patent. Patented Dec. 23, 1919.

Application filed June 26, 1919. Serial No. 306,916.

To all whom it may concern:

Be it known that I, NOBLE R. MEDEARIS, a citizen of the United States, residing at Winston-Salem, in the county of Forsyth 5 and State of North Carolina, have invented certain new and useful Improvements in Indexes for Rubber Stamps, of which the following is a specification.

This invention relates to stationery and 10 more particularly to rubber stamps.

The primary object of this invention resides in the provision of an index for rubber stamps whereby the front of the stamp can be readily determined and the subject matter of the stamp set forth.

With this and other objects in view, this invention resides in certain novel features of construction and arrangement of parts to be more particularly set forth in the specification herewith and pointed out in the appended claim, it being understood that the right is reserved to resort to such changes in construction as come within the scope of the claim.

Figure 1 is a perspective view of a rubber stamp as constructed in accordance with this invention;

Fig. 2 is a cross sectional view on line 2-2 of Fig. 1.

In the present embodiment of this invention, the numeral 5 designates a rubber printing die which is secured in any approved manner to a base 6 of any suitable form.

Formed in one side of the base 6 is a

channel 7 which communicates throughout its length with grooves 8 of sufficient width to accommodate an index card 9.

This index card 9 is retained inwardly from the surface of the base so that the printed matter thereon will be disposed out of contact with other articles coming in contact with the base. With this index card so disposed it will readily indicate the front of the stamp and through the provision of sufficient printed matter thereon, it will distinguish the subject matter of the stamp.

From the foregoing it will be noticed that I provide a hand stamp base having oppositely positioned integral outstanding webs along opposite edges, each web being provided with a channel extending inward in alignment with the face of said base, and a card held in said channels.

With this invention fully set forth it is apparent that an index for rubber stamps is provided which is cheap of manufacture and readily adapted to perform the functions of its adoption.

Having fully described this invention what I claim is:

In combination with a base of the class described having oppositely positioned integral outstanding webs along opposite edges, each web being provided with a channel extending inward in alignment with the face of said base, the said channel adapted to receive and retain the edges of a card.

In testimony whereof I affix my signature.

NOBLE R. MEDEARIS.
